SLOTTED TURBINE BLADE

Edward A. Stalker, Bay City, Mich.

Application January 24, 1947, Serial No. 724,103

6 Claims. (Cl. 253—39.15)

1

This invention relates to turbine blades and particularly to turbine blades incorporating means to keep them cool.

In my patent application, Serial No. 510,884 filed November 19, 1943, now Patent No. 2,489,683 issued November 29, 1949, I have disclosed a blade having nose slots for the emission of a cooling layer of fluid which is emitted in such a manner as to interpose itself as an insulating layer between the hot motive gases of the turbine and the blade wall.

The present invention is directed to a blade construction by which the slots can be incorporated into the blade practically and economically.

An object of this invention is to provide a turbine blade with a specially formed slot.

Still another object is to provide a blade structure with slots which is practical and economical to make.

The above objects are accomplished by the means illustrated in the accompanying drawings in which—

Figure 1 is a perspective of a blade showing the nose slots;

Figure 2 is a spanwise section taken along line 2—2 in Fig. 3;

Figure 3 is a chordwise section along line 3—3 in Fig. 1;

Figure 4 is a plan view of a sheet before forming into a blade;

Figure 5 shows the steps of bending the sheet of Fig. 4 into a blade;

Figure 6 is a fragmentary section along line 6—6 in Fig. 4;

Figure 7 illustrates a tubular blank for use in another method of forming the blade;

Figure 8 is a fragmentary view of the blank showing the platelets cut on the blank;

Figure 9 is a fragmentary section taken along the line 9—9 in Fig. 8;

Figure 10 shows the platelets of Fig. 9 bent down to form narrow slots therebetween;

Figure 11 is a fragmentary perspective view of the blade as viewed looking toward the nose;

Figure 12 is a section along line 12—12 in Fig. 11; and

Figure 13 shows a blade blank being slotted by a conical saw.

Referring particularly to the drawings Figs. 1 to 3 show the desired form of the turbine blade. The blade 10 is composed of the surface 12 and the blade hub 14, the former being welded to the latter at the localities 16 and 18.

The blade is hollow and carries within a cooling fluid flow, preferably air which is discharged through the nose slots 20.

2

The nose slots are formed by overlapping side walls of the platelets forming slots which extend substantially transversely to the leading edge or span of the blade and with legs on both upper and lower surfaces of the blade having a spanwise component of direction toward the same end of the blade i. e., away from the end having the fluid admission opening. The slots are thus crescent or chevron shaped to direct the slot flow 26 along the blade surface, both spanwise and chordwise and along both upper and lower surfaces for a wide range of locations of the stagnation point 28 of the main flow 24.

The fluid emitted from the slots provides an insulating layer of cooler air between the hot gases of the turbine and the walls of the blade. This shape provides for the proper functioning of the protective flow for the stagnation point on either the upper or lower surface of the nose. The theory of this insulating layer has been discussed in my pending application mentioned earlier.

Since the slot walls must be formed to direct the flow along the blade surface the platelets 30 which overlap to form the slots should be curved chordwise and the portion of the slot wall overlapped by the opposite wall must have a generous radius in order to insure that the flow follows the surface without separating therefrom. It is difficult to achieve such slot form but the present invention discloses a blade in which this is accomplished in an economical and practical manner.

In one form of the invention, Figs. 4 to 6, a sheet or blank 40 of metal is formed with a substantial thickening or hump 42. By suitable milling, sawing or the like, the slots 20 are formed in the hump, giving a chevron like appearance to the blank along the hump.

Next the blank is bent or folded and forced into the shape of the blade 12 as shown in Fig. 5 through intervening steps such as 44. The edges of the blank are joined as by welding together at the trailing edge 46.

The side walls of the slots which are the platelets 30 are pressed or forged to have the nose curvature of the blade.

In another form of the invention shown in Figs. 7 to 12, a tubular blank 60 is formed with a nose hump 62 extending along the tube axis. Preferably there is also a trailing edge thickening 64. The tubular blank is formed by extruding or rolling or some other process. Next the blank is cut chordwise along the nose hump to form the plurality of spaced platelets 68. Holes 70 are pierced through the wall between the

platelets. Preferably the platelets are inclined to the axis of the tube as a result of the cutting process, as shown most clearly in Fig. 9.

In the next step the platelets are bent over as shown in Fig. 10 to provide the narrow slots 20 therebetween. Subsequently the tubular blank is deformed into the blade shape shown in Fig. 11 which is similar to that shown in Fig. 1 where the blade is equipped with the blade hub 14.

Fig. 12 shows that the platelets are curved 10 properly in the chordwise direction along the overlapped portions which is very important.

Fig. 12 also shows the blade cross section with the thickening 64 shown dotted at the trailing edge. This portion 64 after the main shape of the blade has been established is cut off to give the 15 sharp trailing edge rather than a blunt or rounded one, and the interior is well rounded at 72 so as to preclude fatigue failures which ordinarily start at acute angles in the surface.

In still another form of the invention, shown in Fig. 13 the tubular blade blank 80 is formed with a thickened wall 82 at the nose. The slots 84 in the nose are cut with a conical saw. That is the saw blade 86 is conical with a circular cross section and the teeth are cut in the small diameter end. The saw blade is rotated about the axis 90 of the cone and is fed into the work along the direction 92 parallel to one side of the cone.

The saw cuts a slot curved chordwise in the turbine blade nose and inclined to the nose surface. These slots are cut through the thickness of the nose wall to establish communication with the spanwise slot 94 cut in the nose to extend spanwise. The slots are fed air from the interior 35 of the turbine blade.

In the practical case with small turbine blades the saw will cut too wide a slot since the saw blade thickness becomes impractical when reduced to a few thousands of an inch. Therefore the slots are cut in a practical size and subsequently the walls of each slot are pressed together to produce the correct slot width.

In Fig. 13 I have shown a blade blank already formed into a blade section into which the saw is cutting. The blank could be a circular tube which would be deformed into a blade section after the slots are cut.

In Fig. 13 I have shown a saw having teeth cut on the end of a conical surface. However this surface could be a cylindrical surface or any other curved surface with the teeth in the free end. Preferably the toothed contour is closed for insuring the strength of the tool but a segment of such a curved surface could also be employed. I call such tools curved end cutters.

It will now be clear that I have disclosed a novel and useful turbine blade which can be maintained in a relatively cool state in the hot motive gas flow through the turbine, and I have described a practical and economical method of producing such a blade with proper slot width and form in both the spanwise and chordwise directions.

While I have illustrated a specific form of this invention it is to be understood that I do not intend to limit myself to this exact form but intend to claim my invention broadly as indicated by the appended claims.

I claim:

1. In combination to form a slotted turbine blade, a sheet metal tube having a blade cross section, said tube having inclined spaced platelets disposed spanwise along said tube and fixed thereto, each said platelet lapping a spanwise 75

succeeding platelet to form a chevron shaped slot therebetween with the apex of said slot being substantially at the stagnation point for discharging fluid tangentially along the exposed 5 surface of said succeeding platelet from within the blade with substantial spanwise as well as chordwise components of velocity providing for a flow of fluid across the exposed surface of each said platelet toward the same end of said blade, the wall of said tube having openings there-through from the tube interior to said slots, said fluid providing an insulating layer of air on the blade surface to exclude heat from turbine gases.

2. In combination to form a slotted turbine blade, a sheet metal tube having a blade cross section, and inclined spaced platelets disposed spanwise along the nose portion of said tube, said platelets being curved in the chordwise direction, each said platelet lapping a succeeding platelet to form a slot therebetween having legs on both upper and lower surfaces of the blade with the apex thereof substantially coinciding with the stagnation point of the flow to produce on both blade surfaces a spanwise component of direction toward the same end of the blade for discharging fluid tangentially along the exposed surface of said succeeding platelet from within the blade with substantial spanwise as well as chordwise components of velocity providing for a flow of fluid across the exposed surface of each said platelet, the wall of said tube being perforated to provide communication between said slots and said tube interior.

3. In combination to form a slotted turbine blade, a sheet metal tube having a blade cross section, and inclined spaced platelets disposed spanwise along the nose portion of said tube, said platelets being curved in the chordwise direction, each said platelet lapping a succeeding platelet to form a slot therebetween having legs on both upper and lower surfaces of the blade with the apex thereof substantially coinciding with the stagnation point of the flow to produce on both blade surfaces a spanwise component of direction toward the same end of the blade for discharging fluid tangentially along the exposed surfaces of succeeding platelets on both upper and lower blade surfaces with substantial axial and chordwise components of velocity providing for a flow of fluid across the exposed surface of each said platelet, the wall of said tube being perforated to provide communication between said slots and said tube interior.

4. In combination to form a slotted turbine blade, a sheet metal tube having a blade cross section, and inclined spaced platelets disposed spanwise along the nose portion of said tube, each said platelet being curved in the chordwise direction and having an oval-like contour, each said platelet lapping an axially succeeding platelet to define slots therebetween, the exits of said slots defining a plurality of chevron shaped lines distributed along the blade nose with the apex thereof at substantially the stagnation point of the flow, and means to supply fluid to the spaces between platelets for discharge over the exposed surface of each of the platelets to insulate it from exterior hot gas.

5. In combination to form a slotted turbine blade, spaced walls enclosing a hollow interior and shaped to a blade contour and having upper and lower exposed surfaces, a nose portion joining said walls at the forward end of said blade, means on said blade defining a plurality of spanwise spaced slots extending generally transversely

of said nose portion and adapted to discharge a series of overlapping air jets in protective relation to the surface thereof, said blade having an opening into its hollow interior to admit a flow of fluid for discharge through said slots, said slots having inclined legs extending to the upper and lower surfaces of said blade with a spanwise component of direction on each said surface toward the same end of the blade and meeting in an apex located substantially at the stagnation point of the flow.

6. In combination to form a slotted turbine blade, spaced walls enclosing a hollow interior and shaped to a blade contour and having upper and lower exposed surfaces, a nose portion joining said walls at the forward end of said blade, means on said blade defining a plurality of spanwise spaced slots extending generally transversely of said nose portion and adapted to discharge a series of overlapping air jets in protective relation to the surface thereof, said blade having an opening at one end thereof into its hollow interior to admit a flow of fluid for discharge through said slots said slots being substantially

5 chevron-shaped and extending to the upper and lower surfaces of said blade with the apex substantially at the stagnation point and with each leg having a spanwise component of direction on each said surface away from the end of said blade having said fluid admission opening.
